(57) **CLAIM**

The ornamental design for a soft protective headgear for infants, substantially as shown and described.

DESCRIPTION

FIG. 1 is a top isometric view of a soft protective headgear for infants showing my new design;

FIG. 2 is a top plan view thereof;

FIG. 3 is a front elevational view thereof;

FIG. 4 is a rear elevational view thereof; and,

FIG. 5 is a side elevational view thereof; the opposite side being a mirror image.
